UNITED STATES PATENT OFFICE

108,725

DESIGN FOR A COMBINED TOOTH PASTE DISPENSER, GLASS AND BRUSH HOLDER

Harry C. A. Behr, York, and Carroll H. Sweitzer,
New Freedom, Pa.

Application December 31, 1937, Serial No. 74,034

Term of patent 14 years

To all whom it may concern:

Be it known that we, Harry C. A. Behr and Carroll H. Sweitzer, citizens of the United States, residing at York and New Freedom, respectively, in the county of York and State of Pennsylvania, have invented a new, original, and ornamental Design for a Combined Tooth Paste Dispenser, Glass and Brush Holder, of which the following is a specification, reference being had therein to the accompanying drawing, forming part thereof, in which

Figure 1 is a perspective view of a combined tooth paste dispenser, glass and brush holder, showing our new design.

Figure 2 is a view in side elevation.

Figure 3 is a bottom plan view.

We claim:

The ornamental design for a combined tooth paste dispenser, glass and brush holder, as shown.

HARRY C. A. BEHR.
CARROLL H. SWEITZER.
